METHOD OF TREATING GASES.

1,083,232

specification of Letters Patent.

Patented Dec. 30, 1913.

Application filed April 21, 1911. Serial No. 622,463.

To all whom it may concern:

Be it known that we, CHARLES A. WEEKS and RUDOLPH M. HUNTER, both citizens of the United States, and residents of the city and county of Philadelphia and State of Pennsylvania, have invented an Improvement in Methods of Treating Gases, of which the following is a specification.

Our invention has reference to a method of 10 treating gases and consists of certain improvements which are fully set forth in the following specification and shown in the accompanying drawings which form a part thereof.

15 The object of our invention is to provide a method and means which shall be adapted to subject waste or other gases from industrial or other processes to treatment in such manner that the said gases are caused to 20 flow under suction produced by our invention and, during such flow, be subjected to condensing and scrubbing actions, preferably with densification or compression, whereby the gases may be purified and the 25 by-products previously contained in the said gases, may be recovered.

In some uses of our invention the sulfur or other suspended or associated condensable by-products such as ammonia, may be 30 recovered and the purified gases allowed to go to waste, whereas in other cases the gases may be the essential product to be preserved and utilized after purification; and yet, again, in other cases, both the by-products 35 and the gases are to be utilized after being separated.

In the practice of our invention, the gases are preferably removed from the coking or other ovens or sources, under a partial 40 vacuum and at approximately the lowest temperature at which they are formed in the first part of the destructive distillation; and in the particular case of the products from coking ovens, such gases would be 45 those containing tar, sulfur, ammonia and cyanogen. These products, from the distillation of the coal in the coking ovens, are exhausted in a positive manner from one or more ovens at a time and conveyed to a distance, where they are cooled and condensed by action of water, into contact with which they are brought by the improved apparatus hereinafter described, said action being such that the gases are treated to a posi-

tive washing or scrubbing and preferably 55 with densification, said densification being mechanically produced. The object of the densification is twofold, namely, to more readily induce the condensation of the condensable gases and to insure more intimate 60 contact with the washing water for precipitating or dissolving out the by-products.

By conducting the destructive distillation under a partial vacuum and hence without back pressure, and more especially without 65 the necessity of draft due to combustion, we are enabled to cause the generation of the gases from the coal, to take place more readily and rapidly and all of the gases produced may be collected and subjected to the process 70 for the recovery of by-products.

More specifically considering our invention as applied to the purpose of recovery in connection with the commercial coking of coal as an example of the practice of our 75 process, we arrange the ovens in a row and adapt them to be operated in pairs, that is to say one oven of a pair to be under process of destructive distillation while the other oven of the pair is having its contents 80 quenched, discharged and is being charged, and vice versa; the products from the destructive distillation being conveyed from the trunnel head of the oven by a suitable conduit or main; and the products in said 85 main being drawn away from the ovens under suction, due to a partial vacuum created by the special construction of the condensing and recovering appliances. After the first part of the coal distillation has been 90 completed and the fire has been put under way in the recharged other oven of the pair, an adjustable conduit section is shifted to the trunnel head of said second oven to convey the distillates to the recovery apparatus; 95 and the first mentioned oven is thus opened to the atmosphere and its contents allowed to burn for a given length of time to finish the carbonizing necessary to secure a good hard metallurgical coke. When this is 100 done, the contents are quenched and the cooled coke product pushed out of the oven. The oven is then recharged and the process repeated. In this manner the recovery process, as a whole, is conducted in a continuous 105 manner, although the ovens of a pair are being alternately heated and cooled.

The suction produced by the condensing and washing apparatus is continuous and although it is somewhat interfered with by the momentary shifting of the conduits from 5 one funnel head to the next, this shifting of the conduits does not materially interfere with the effectiveness of the process, while it does simplify the apparatus by obviating extra conduits and valves which would be 10 otherwise necessary. By passing the gases which distil from the coal in the first part alone of its treatment, to the recovery apparatus, it is evident that the said apparatus will not be compelled to have capacity 15 for handling the later gases also, such gases being largely carbonic acid and very lean in recoverable products. If, for any reason, it is desired to utilize these later gases, preliminary to quenching, it should be done 20 by a second set of conduits so as not to require them to be passed through the recovery plant.

The distillates, which convey the recoverable values, are first separated from the tar 25 and then passed through a hydraulic seal and partly cooled and are then passed to the condenser and washer, where they are further cooled to a temperature of about 85° Fahrenheit. We may assume that the temperature within the oven reaches as high as 30 2600 or 2700 degrees Fahrenheit and the gases leaving the trunnel heads are from 1800 to 2000 degrees Fahrenheit and at this temperature are started on their travel to 35 the condenser and washer. The gases are somewhat cooler by the time they reach the hydraulic seal or cooler but practically none of the distillates are condensed except the tar. In passing through the hydraulic seal 40 the temperature of the gases is reduced to about 120° to 130° Fahrenheit and at this temperature enters the condenser and washer; and in passing through this apparatus the temperature is gradually lowered 45 to about 75° Fahrenheit. From the condenser and washer the gases are allowed to go to waste or may, in their purified condition, be utilized for operating explosive engines, for heating purposes or illuminating 50 after having been impregnated with hydrocarbons in the usual way.

During the reducing of the temperatures of the gases and the treatment to the water, the by-products are extracted from the gases 55 and recovered in the water, but care should be had not to reduce the temperatures too much or too suddenly or otherwise undesirable quantities of lamp black and naphthalene will be formed which, while not being of value as a by-product, acts as an objectionable clog to the pipes and machinery. Lamp black is necessarily found in all coal tar produced by carbonization; but the natural quantity to be expected may be objectionably increased if care is not exer-

cised against sudden reductions in temperature when free carbon is present and before the carbon has combined with other elements.

Naphthalene is a hydrocarbon and produced as a distillate of coal at a high temperature and finds its way into the tar. Its tendency to form flaky deposits of hard nature when cooled is objectionable and while it may be removed by separate treatment of the gases before the by-products are extracted, its objection may be considerably reduced by avoidance of sudden reductions in temperature of the gases, such naphthalene as may be formed may be removed with the tar.

Aside from the recoveries of the tar and its contained compounds, the most important of the by-products recoverable from coal distillation by our process is ammonia, 75 this amounting to about nine gallons of 61° Twaddell and twelve gallons of 3° Twaddell ammoniacal liquor per ton of coal used. The recovery of tar approximates 19½ pounds from the ton of coal so employed. 80 It is, of course, to be understood that sulfur and other products may be equally recovered, but the presence of these substances depend upon the composition of the materials being treated in the ovens and in giving the use of our invention in connection with the making of coke we do not intend to restrict ourselves thereto.

In the condensing and washing or scrubbing treatment, we produce a partial vacuum which, acting through the hydraulic seal, sucks the gases from the ovens, thereby facilitating the distillation process and enabling it to be carried on at a lower temperature. Moreover, by inducing the gases 105 to flow through the main under a tendency to rarefaction, there is less liability to deposition of carbon and naphthalene, this of course, due to the fact that the temperature in the main near the ovens is relatively quite 110 high. The partial vacuum prevents all choking of the conduits and precipitation of lamp black or carbon deposit and in general reduces the time required to change the oven charge to coke. More especially, is the use 115 of the partial vacuum important in extracting the gases, in that it enables the distillation to take place and the by-products to be collected at lower temperature than where natural drafts are employed. In this way 120 not only are more by-products per ton of coal secured, but those by-products, such as sulfur, which comes off with the first distillates in the roasting and before internal combustion actually begins, may be recovered 125 instead of being allowed to go to waste, as heretofore.

The partial vacuum is produced in our invention by a revolving cylinder having its interior formed with a helical division, the 130

pitch of which decreases from the intake end to the discharge end, said cylinder being partly submerged in water and rotated at preferably a slight angle, and having, furthermore, its intake end and its discharge end opening into separate chambers. The operation of the cylinder is to remove bodies of the gases in rapid succession from the intake or vacuum chamber and transfer them to the discharge chamber, said gases during passage being subjected to the cooling, condensing and washing or scrubbing action to separate the recoverable products. During this treatment, the gases are compressed so as to be more thoroughly condensed and washed and further, so as to be forcibly discharged through the water at the discharge end.

Our invention will be better understood by reference to the accompanying drawings, 20 in which:

Figure 1 is an elevation of apparatus in which to carry into practice our improved process; Fig. 2 is a cross section of the coking ovens; Fig. 3 is a plan view of the coking ovens; Fig. 4 is a longitudinal sectional elevation of our improved means for condensing and washing the gases and creating the partial vacuum under which they circulate; and Fig. 5 is a perspective view of one 30 end of the cylinder of the condenser and washer.

2 represent the furnaces or ovens from which the gases to be treated are taken; as shown these ovens are of the form used for 35 coking coal. They have side openings 5 through which the coke is discharged, said openings being closed by doors 4 during the coking operation. The dome or central portion of the ovens have trunnel heads 3 40 through which the gases escape from the ovens and by which the ovens are charged. These ovens are arranged in a row and may be charged from the usual larry (not shown) which runs upon the track to one side of 45 the trunnel heads.

6 is a longitudinal gas flue or main and is located preferably on about the level of the top of the ovens, though we do not restrict ourselves in this respect. This main 6 is provided at intervals in its length with upward branch openings 7 upon which are pivoted the swinging sections of pipe 8 which have their free ends 9 curved downward and adapted to form a tight joint with 50 the trunnel heads 3 of the ovens. There is one of these radially adjustable pipes 8 for each pair of ovens and so positioned that its end 9 may be shifted over the trunnel head 3 of either of said ovens, whereby when the 55 gases from one oven are being drawn off through the pipe 8 into the main 6 the gases from the other oven are allowed to pass to the atmosphere. The swinging pipe sections 60 8 may be supported and guided by the eas- 65 ters 11 running upon the curved rail 12, and

the movement may be facilitated by use of the handle 10.

The end of the main 6 may be provided with a tar collecting trap 41 if so desired to collect the tar instead of passing it into the hydraulic seal 14. The tar may be drawn off from the trap from time to time by a suitable drain pipe having a valve and indicated at 40. The pipe 6, at its end, turns downward and passes into the seal tank 14 to form the seal by having its lower open end 13 dipping into the water, the level of which is indicated by a dotted line. The extent of this water seal may be made to suit the requirements. The hot gases in passing through the main 6 and then through the water are very materially lowered in temperature as before stated, so that they will be in better condition for treatment in the exhausting condenser and 85 scrubber.

The cooled gases pass by pipe 16 from the hydraulic seal into the top of the vacuum chamber 31 within the tank 17 of the combined exhausting condenser and scrubber. Arranged within the tank 17 is a longitudinal cylinder 19 open at the end 27 and closed and perforated at the end 28; said cylinder being further provided with an axial shaft 20 and a helical division 25 extending from the walls of the cylinder to the shaft which forms a helical passage 26 from one end of the cylinder to the other. This apparatus is adapted to rotate and constitutes an exhausting conveyer device for the gases. It will be noticed that the pitch of the helical convolutions 25 decrease from the open end 27 to the other or perforated end 28 and this variation in the pitch may be gradual or otherwise as preferred. The shaft 20 is 90 preferably journaled in bearings 21 and supported at an angle to the horizontal as shown. Stuffing boxes are provided to prevent leakage of the water from the tank where the shaft extends through the bearings.

The shaft may be driven by any suitable means and in the particular construction shown, it is driven by an engine 24 which is connected with the shaft by suitable universal joint 24a.

30 is a partition which separates the receiving chamber 31 from the discharge chamber 32 and extends down into the water within the tank 17 upon each side of the cylinder and at its lower part it forms a connection with a grooved band 29 arranged about the conveyer 19. The gases which are delivered from the conveyer into the discharge chamber 32 are led off by a 120 pipe 18 and may be allowed to go to waste or may be utilized for operating gas engines or for any purpose where purified gases are 125 useful.

If desired, the gases may be carbureted 130

by use of oil and fixing chambers similar to the well known process of making water-gas for lighting purposes.

The interior of the compartment 31 of the tank 17 is preferably provided with downwardly projecting transverse plates or baffles 33 extending from the top plate toward the cylinder 19 and water, and the cylinder 19 may be provided with circumferential flanges 34 arranged at intervals along its length and preferably intermediate of the baffle plates 33. The plates 34 on the cylinder act as baffles to direct the gases upward and the fixed plates 33 act as baffles to project the gases downward. It will be understood that as the conveying cylinder 19 rotates, its outer surface will be wet with the water and this wetting will also be upon the circumferential baffle plates 34. As the gases enter by the intake pipe 16 they will be caused to travel as indicated by the arrows in reaching the intake end 27 of the rotary conveyer. During the passage of the gases from the intake 16 to the end 27 of the conveyer, they will be caused to come in contact with the wet outer surface of the cylinder 19 and the baffles 34 and will be more or less cooled and washed so that less duty will be required of the conveyer 19 which transfers the gases from the chamber 31 to the chamber 32. The baffles 33 and plates 34 may be arranged in any other suitable or convenient manner so long as they operate to present to the gases moving wet surfaces and guide the gases against said wet surfaces in passing from the intake flue 16 to the intake end of the rotary conveyer.

The end of the tank 17 is provided with a large head 23 which is of sufficient diameter to permit the withdrawal of the rotary conveyer, if from any cause such as would require repairs, it is desired to remove the same. The bottom of the tank 17 may be provided with a plurality of vertically extending plates 35 which terminate some distance from one end of the tank so as to provide a plurality of longitudinal grooved portions adjacent to the bottom of the tank and communicating with a transverse passage 36 which may discharge through a valved outlet 37. These plates 35 operate to produce quiescent bodies of water adjacent to the bottom of the tank and assist in permitting the precipitated matters to accumulate in the bottom and not be disturbed by the rotation of the conveyer and scrubber. These longitudinal plates 35 are indicated in Figs. 1 and 4.

The apparatus herein shown may be operated as follows: Considering a pair of ovens 2, while the coke is being completed and cooled and discharged from one oven and the said oven again charged, the gases from the other oven are being sucked off into the main 6 and conveyed to the seal and

exhausting and scrubbing devices. The operation of the rotary conveyer 19 is such that when the same is rotated at a proper velocity the gases are sucked from the ovens through the main 6 and discharged from the pipe 18, said rotary conveyer and scrubber producing a partial vacuum in the chamber 31 and said vacuum extending through the pipes up to the ovens so that the gases from said ovens may be drawn off and properly treated without relying upon any other function to be performed in said ovens other than the production of the gases by the chemical reactions which take place therein. The rotation of the rotary conveyer and scrubber 19 operates to receive large bodies of the gases at the intake end 27 and to then seal said bodies of gases successively and in a rapid manner propel the said gases through the conveyer and above the surface of the water contained therein and being circulated through the same. In this manner the gases which are conveyed through the rotary conveyer are more or less gradually compressed according to the reduction in cubical capacity of the spaces 26 formed between the spirals of the helical division 26, and this propelling of the gases through the conveyer is performed in a most positive and effectual manner. During the passage of the gases through the conveyer, they are subjected to the action of the water within the conveyer over which they are confined, as well as by the scrubbing action which is produced upon the gases by the moving metallic wet surfaces of the conveyer itself. Furthermore, during this operation, the rarefied gases entering at the end 27 are brought to a condition of densification which approximates atmospheric pressure or a pressure above the atmosphere before they leave the discharge end 28 of the conveyer. This compressing of the gases simultaneously with their conveyance insures a better scrubbing action owing to the greater density. It will also be observed that the water which is within the rotary conveyer and employed to scrub the gases contained in the spaces 26 between the spirals, and which water absorbs the ammonia and other substances capable of being absorbed or washed out of the gases, is propelled through the conveyer and discharged therefrom into the body of the water within the tank 17 and required to flow from the discharge end along the bottom toward the intake end wherein it again enters the conveyer. When this water from the conveyer is commingled with the body of the water within the tank 17 and is thereby diluted, it will have less tendency to support any matters in suspension and these matters will, in view of the slower travel of the water be permitted to settle in the grooved spaces between the plates 35, so that the water which

enters the intake end 27 of the rotary conveyer is in a more pure condition than is the water which leaves the discharge end of the conveyer, and hence is in a better condition to extract the ammonia and suspended matter from the gases.

The operation of the conveyer 19 is very positive in its action upon the gases and by varying the speed of rotation any reasonable degree of partial vacuum may be produced in the intake end 31 of the tank found desirable and this partial vacuum will extend its influence all the way to the ovens or other sources from which the gases are produced. It is desirable that the gases in the discharge chamber 32 shall exist at about atmospheric pressure and in some cases slightly above and this may be readily accomplished by the variable pitch construction of the spiral division 25 within the rotary conveyer and without impairing the capacity of the rotary conveyer to produce any predetermined extent of partial vacuum in the intake chambers 31 and the main conduit or flue 6. During the passage of the gases through the condenser and scrubber, the said gases are not only cleansed and made to give up the ammonia and other extractable products, but are also cooled to a very material extent before being discharged from the chamber 32, the said cooling action facilitating the extraction of the products to be absorbed by the water.

When the apparatus is used in coking process, it is customary when the oven from which the gases are being extracted has been in operation approximately twelve hours that the adjustable pipe 8 shall be shifted to the other oven of the pair by connection with the tunnel head 3 thereof, so that the gases given off from the said oven shall be extracted under the partial vacuum existing in the main flue 6. During the twelve hours consumed in the extraction of the gases from this second oven, the contents of the first oven are allowed to cool and after being quenched are discharged and the oven recharged and the operation repeated.

We have shown apparatus suitable for the carrying out of our improved process and especially in connection with coking of coal, but it is to be understood that this apparatus may be varied without departing from the spirit of the invention relating to the process, and as to the apparatus the details thereof may be modified without changing the general construction or mode of operation. For example, there may be a number of helical divisions 25 to increase the number of chambers 26 in place of the use of the single helical division which is shown for simplicity, and it is also to be understood that the inclination of the conveyer cylinder 19 may be increased or omitted without departing from the spirit of the invention.

We, therefore, do not limit ourselves to the details of the apparatus, as these may be changed or modified as may be found expedient in adapting the apparatus for a particular use.

Having now described our invention what we claim as new and desire to secure by Letters Patent is:—

1. The herein described process for treating gases, which consists in generating gases by chemical reaction in a practically closed coking oven, drawing said gases away from the place of generation under the influence of a partial vacuum, subjecting the gases to a combined cooling condensing and scrubbing action in the presence of a body of fluid, and simultaneously subjecting the said gases to the action of less extent of partial vacuum as the said cooling condensing and scrubbing action progresses and causing the gases in separated confined bodies to travel over the body of fluid with gradually slowing movements commensurate with their increasing pressure.

2. The herein described process for treating gases, which consists in generating gases by chemical reaction, drawing said gases away from the place of generation under the influence of a partial vacuum, separating the heavy hydrocarbons from the gases before cooling, passing the gases through a hydraulic seal to reduce their temperature while maintaining the partial vacuum upon both sides of the seal, subjecting the gases to a progressive combined cooling condensing and scrubbing action in the presence of a body of fluid, simultaneously subjecting the said gases to the action of a gradually less extent of partial vacuum as the said cooling condensing and scrubbing action progresses.

3. The herein described process for treating gases which consists in generating gases by chemical action at one place at a pressure less than atmospheric pressure, drawing off said gases and conveying them to a distance by the action of a partial vacuum, subdividing the gases so existing at a pressure below atmospheric pressure into separate successively produced bodies, and independently treating the several bodies of the gases to the action of a cooling and scrubbing fluid by causing said bodies of the gases to travel in confined condition with a gradually decreasing speed and increasing pressure in passing from the vacuum zone to a zone of atmospheric pressure.

4. The herein described process for treating gases which consists in simultaneously generating gases in a plurality of furnaces by chemical action at a pressure less than atmospheric pressure, drawing off and mixing said gases and conveying them to a distance by the action of a partial vacuum, subdividing the mixed gases so existing at a pressure below atmospheric pressure into

separate successively produced bodies of average mixture, independently treating the several bodies of the gases to the action of a cooling and scrubbing fluid, gradually reducing the vacuum under which the successive bodies of mixed gases exist during their treatment to cooling and scrubbing, delivering the gases at atmospheric pressure, and finally separating the fluid with its by-products from the current of gas being treated.

5. The herein described process for treating gases which consists in producing a difference in pressure between two chambers by maintaining a partial vacuum in one of them, maintaining an intermittent communication between the chambers by transferring isolated bodies of gases successively from the chamber containing the partial 15 vacuum to the other chamber at a gradually decreasing speed and subjecting said isolated bodies of gases to a cooling and scrubbing action with water, reducing the partial vacuum of the respective isolated bodies of 20 gases during their treatment to increase the scrubbing action, supplying the gases from a source in a heated state under the partial vacuum to the chamber in which the partial vacuum is maintained, and delivering the 25 cooled and scrubbed gases from the other chamber in a purified and cooled condition under a pressure greatly in excess of that at which they were delivered into the chamber in which the partial vacuum exists.

30 6. The herein described process of continuously treating gases of coking ovens and separating by-products therefrom, which consists in alternately operating two ovens under partial vacuum and atmospheric pressure by which gases are generated in one oven while the other oven is cooling its contents discharging the same and being recharged and vice versa, maintaining a partial vacuum in a main common to both of 35 said ovens and moving the gases therein horizontally at a pressure below atmospheric pressure, connecting said main alternately with said ovens so that gases will be 40 alternately drawn off from the two ovens into the main under the same conditions, maintaining a moving body of water and isolated bodies of gases between two chambers whereby the isolated bodies of gases are transferred with such rapidity as to produce 45 and maintain a partial vacuum in one of the chambers, delivering the gases from the main into the chamber in which the partial vacuum is maintained, maintaining the partial vacuum in the main leading to the 50 ovens by the partial vacuum in the chamber, and depositing the by-products from the 55 gases during the treatment of the isolated 60 ovens by the partial vacuum in the chamber, and depositing the by-products from the gases during the treatment of the isolated

bodies of gas with the moving body of water.

7. The herein described process of continuously treating gases of coking ovens and separating by-products therefrom, which consists in alternately operating two ovens under partial vacuum and atmospheric pressure by which gases are generated in one oven while the other oven is cooling its contents discharging the same and being recharged and vice versa, maintaining a partial vacuum in a main common to both of said ovens, connecting said main alternately with said ovens so that gases will be alternately drawn off from the two ovens into the main under the same conditions, maintaining a moving body of water and isolated bodies of gases between two chambers whereby the isolated bodies of gases are transferred with such rapidity as to produce and maintain a partial vacuum in one of the chambers, gradually increasing the absolute pressure of the bodies of the gases during 85 their transference, delivering the gases from the main into the chamber in which the partial vacuum is maintained, maintaining the partial vacuum in the main leading to the ovens by the partial vacuum in the chamber, 90 interposing a water-seal between the gases in the main and the gases in the chamber in which the partial vacuum is maintained for cooling the gases and for maintaining the vacuum in the chamber when shifting 95 connection of the main with the two ovens, and depositing the by-products from the gases during the treatment of the isolated bodies of gas with the moving body of water.

8. The method of treating gases which consists of intermittently drawing the gases out of one chamber with such rapidity as to produce a partial vacuum therein, supplying hot gases to said chamber in quantity insufficient to destroy said partial vacuum, delivering the gases so drawn out of the said chamber into a second chamber in which a higher pressure exists, confining the bodies of the gases so transferred and retarding the speed of movement as their transference progresses, and during the passage of the intermittently withdrawn confined bodies of gases from one chamber to the other subjecting the said bodies of gases to a cooling condensing and scrubbing action of a fluid.

In testimony of which invention, we hereunto set our hands.
